Inventor

Thomas S. Miller
By Alpheus G. Attorneys.

UNITED STATES PATENT OFFICE.

THOMAS S. MILLER, OF THE GROVE, TEXAS.

VEHICLE-HUB.

SPECIFICATION forming part of Letters Patent No. 307,789, dated November 11, 1884.

Application filed January 16, 1884. (Model.)

To all whom it may concern:

Be it known that I, T. S. MILLER, a citizen of the United States of America, residing at The Grove, in the county of Coryell and State of Texas, have invented certain new and useful Improvements in Wagon and Buggy Hubs, of which the following is a specification, reference being had therein to the accompanying drawings.

10 My invention pertains to an improvement in vehicle-wheels; and it consists in the peculiar construction, combination, and arrangement of the parts, whereby a single damaged spoke may be removed and a new spoke inserted without releasing the several spokes comprising the wheel; in the construction of the wedges for such removal; in providing in the hub-section A³ a recess, a', adapted for reception of washers a, for forcing the wedges, 20 and nut-lock A⁵, serially pointed and screwed to tubular box B, and adapted to corresponding grooves in sections A³, substantially as hereinafter more fully set forth and claimed.

In the accompanying drawings, Figure 1 is 25 a longitudinal section of my improved wheel-hub. Fig. 2 is a perspective view with the wedges and the nut moved a short distance from the remaining parts. Figs. 3 and 4 are detail views. Fig. 5 is a perspective view of 30 one of the wedges. Fig. 6 is a form of lock-nut which may be used with my invention. Fig. 7 is a withdrawing device for the wedges, and Fig. 8 shows in a slightly-enlarged plan view the manner in which it is applied.

35 In the construction of my vehicle-wheel the box of the hub is preferably made of the detachable malleable-metal sections A² and A³. A' is a hollow cast-metal conical wedge or box fitted into the hub-section A².

40 B represents wedges, which are forced in the space between the inner side of the mortised end of the section A² and section A³, (which latter receives the inner enlarged ends of the spokes,) and the smaller portion of the conical wedge A'. The outer surfaces of the wedges are thus forced against and firmly wedge the inner ends of the spokes into the aforesaid mortises of section A², while the inner tapering ends of said wedges enter the annular 45 space K of said section A², which allows for the further wedging movement of the wedges

in compensating shrinkage. The hollow conical wedge or box A' tapers from rear to front to correspond with the coincident taper of the wedges B, and as each wedge is forced with a 55 distinct pressure upon a coincident spoke the outward pressure upon the spokes is rendered uniform, and the felly is held rigidly against the tire, and the tendency to loosening from unequal pressure against the ends of the spokes 60 is obviated. These wedges thus arranged are readily and firmly tightened by rotating the same with a wrench applied to an octagonal shoulder, b, Fig. 1, which is cast integral with section A³. When hub-section A³ is thus rotated upon the threaded end of tubular box 65 B', washer a in recess a' is forced against the wedges B. The washers i are designed for making a close joint in adjusting the sections. Section A³ is secured against rotation by a nut-lock A⁵, as is more plainly shown in Fig. 6, 70 having a serially pointed disk-nut, which is fitted into a recess or housing, b', of section A³, the recess, Fig. 7, having grooves or channels corresponding to the serially pointed disk-nut. The nut-lock A⁵ is apertured at b² for 75 reception of screws, which screw into corresponding apertures, b², Fig. 6, provided in the tubular box B, as shown in Fig. 7. The tubular box B is rigidly secured in hub-section A² 80 as against turning by ribs l, cast thereon, which, entering notches or recesses in said section, extend through the center of the hub, as shown, and it is provided with a screw-threaded extension, A⁴, adapted to the female screw 85 in the center of the hub-section A³. Hub-box section A³ comprises the outer end of the hub, and is provided with a recess, a, and into this recess the outer ends of the wedges B fit, the shoulder a being brought into contact with the 90 washer a', and thus the wedges B, when tightened, are made to slide upon the conical wedge A'.

As seen in Fig. 7, I provide a device for withdrawing the wedges B in removing the 95 spokes or a spoke, the hook end thereof being inserted into the notches of said wedges, while its upturned end is struck with a hammer when said operation is performed.

It will be observed that this peculiar construction and arrangement of parts enables 100 the tire to be tightened without opening the

hub; that the outward pressure upon the ends of the spokes is rendered uniform; that the outside portion of the hub acts as a nut, the latter being secured as against loosening by a 5 nut-lock, as before stated; and that the use of an interior thimble and nut, which works loose and renders this class of wheels objectionable and unreliable, is wholly avoided, and that by casting the hub-box section A² sepa- 10 rately from the hollow wedge or box A' the latter can be renewed when worn without requiring the making of an entire new hub; and it will also be observed that a single spoke 15 injured or unsuitable may be removed and re- placed with a new one without releasing the several spokes comprising the wheel, and that the wedges are adapted by their peculiar construction to admit of removal of a single spoke at a time.

20 I am aware that it is not broadly new to

tighten the spokes of vehicle-wheels by use of a cone-wedge fitted between the box and the hub-sections, and that a nut-lock has also been used upon vehicle-hubs.

Having thus fully described my invention, 25 what I claim, and desire to secure by Letters Patent, is—

A vehicle - wheel consisting of section A², conical wedge or box A', having ribs l, tubular screw A⁴, and apertures b³, section A³, having 30 recess a for washers a', nut-lock A⁵, and conical wedges B, having notches F for their separate removal, substantially as shown, and for the purpose described.

In testimony whereof I affix my signature in 35 presence of two witnesses.

THOMAS S. MILLER.
